HEATING SYSTEM FOR COKE OVENS

Alan Taylor and Albert Norman Clark, Guildford, England, assignors to Woodall-Duckham (1920) Limited, Guildford, England, a British company

Application September 11, 1940, Serial No. 356,398
In Great Britain September 11, 1939

2 Claims. (Cl. 202—151)

This invention relates to improvements in heating systems for coke-ovens.

The invention is applicable to ovens heated by rich gas (e. g. coal gas) only, and also to the so-called "combination ovens" which are adaptable for heating either by rich gas or by a lean gas such as blast-furnace gas.

When rich gas and air are supplied together to the base of a heating-flue of a coke-oven, the rapid combustion of the rich gas tends to liberate excessive heat in the lower part of the flue, with the result that there is a tendency for the lower part of the flue (and consequently the adjacent part of the charge in the oven) to be overheated, while the flame does not extend fully to the top of the flue, which is correspondingly underheated. Various proposals have previously been made for obtaining uniform heating with rich gas firing; for example, a portion of the products of combustion have been returned to the base of the flue to dilute the combustion gases and so lengthen the flame. It has also been proposed to begin the combustion at alternate low and high levels in successive flues, so that on the average the heating is uniform over the full height of the oven.

The object of the invention is to provide a heating system for coke-ovens in which, when the heating is effected by rich gas, the heat is uniformly distributed over the entire height of the oven.

According to the present invention, in a coke-oven having vertical up-burning heating-flues, rich gas for combustion is introduced into each flue at the same level and at a substantial distance above the base of the flue through an orifice adapted to give a vertical non-turbulent stream of gas, and combustion air is introduced into the base of the flue through an orifice also adapted to give a vertical and non-turbulent stream of air, and the rich gas and the air enter the flue at approximately equal velocities.

A further feature of the invention consists in the introduction of the rich gas to each flue through a vertical tubular member supported on the base of the flue.

The application of the invention to a coke-oven is illustrated in the accompanying drawings, in which

Figure 1 shows a vertical longitudinal section through a coke-oven battery, the right-hand portion being a section through the oven, and the left-hand portion a section through the heating-flue system.

Figure 2 is an enlarged sectionalised perspective

view of the base of a heating-flue embodying the invention, and

Figure 3 is an enlarged section through the base of a heating-flue on the line A—A of Figure 1.

5 Referring to the figures, 4 is the coke-oven in which coal is coked by the heat generated by the combustion of fuel gas and air in the heating-flues 5. When the oven is heated by rich gas (e. g. coal gas) the rich gas may be supplied to the lower end of the flues 5 through the gas duct 6 and the regulating nozzles 7, which latter are situated at the bottom of a well 11 extending below the base of the flue 5, while combustion air, preheated in the regenerators 8, is supplied through the passages 9. When the oven is of the kind known as an "Underjet-fired oven" the rich gas is supplied in controlled amounts to the flues 5 from distributing headers situated in the oven basement below the regenerators, through vertical ducts in the vertical division walls between the regenerators, the air supply to the flues being as before. If the ovens are arranged as "combination ovens" then, when operating on lean gas (e. g. blast-furnace gas) the lean gas is preheated in one set of regenerators and the air is preheated in another set of regenerators, and the streams of preheated gas and air are fed together to the flues through the passages 9.

10 In accordance with the present invention the rich gas (whether supplied through the duct 6 or by an underjet system) is led into the lower end of each flue 5 through a vertical refractory tube 10 arranged as a continuation of the well 11. The rich gas outlet from the tube 10 is at the same 15 fixed level in each flue 5 of the heating wall, at a level of, say, nine to fifteen inches above the base of the flue 5 in the case of a flue nine feet high. The gas pressure and the dimensions of the tube 10 are so co-related that the correct amount of 20 gas enters the flue in a vertical jet which is, as far as is practicable, non-turbulent.

25 The combustion air enters the base of the flue through the port 12 formed at the junction of the passages 9. The port 12 has smooth sides adapted to give, as far as is practicable, a streamline (non-turbulent) form to the vertical stream of air entering the flue.

30 Further, in accordance with the present invention, it is arranged that the velocities of the air stream from the port 12 and of the gas stream from the tube 10 are approximately equal. Hence 35 the gas and air ascend the flue in parallel streams at approximately equal velocities, commingling only slowly owing to the absence of excessive 40 turbulence in the streams, and thus providing a 45

gradual combustion extending over the greater part of the height of the flue, below the gas tube 10 being effectively heated by radiation from the flame. In this manner, an average uniform heating is effected over the full height of the oven 4.

An advantage of introducing the air stream through the port 12 below the opening of the gas tube 10 is that eddies created at the mouth of the port die away or diminish in the interval before the gas stream is encountered.

We claim:

1. In a heating system for coke ovens having a series of vertical heating flues and means for supplying air and rich gas to said flues; means providing each of said flues with a transverse bottom wall, the bottom wall of each flue having a vertically disposed well opening downwardly from said flue, each of said wells communicating with said rich gas supply means at the lower end of the wells; a gas regulating nozzle of lesser diameter than said well disposed at the bottom of

each said well and affording the sole means of communication between said rich gas supply means and the respective wells; and a tubular burner nozzle disposed within each flue at the upper end of the well whereby to deliver rich gas from said well to said flue in a non-turbulent stream at a point appreciably above the bottom wall of the flue, the bottom wall of each flue being provided with an air duct communicating with 10 said air supply means and opening into said flue at a point below the top of said burner nozzle and exterior thereto.

15 2. The apparatus described in claim 1, wherein said tubular burner nozzles are of substantially the same internal diameter as said wells and are removably supported on the bottom wall of the flues within annular shoulders concentrically disposed with respect to said wells.

ALAN TAYLOR.
ALBERT NORMAN CLARK.
